UNITED STATES PATENT OFFICE.

ELWOOD T. McGINNIS, OF ATLANTIC CITY, NEW JERSEY.

COIN-HOLDER.

1,271,339.

Specification of Letters Patent.

Patented July 2, 1918.

Application filed November 25, 1916. Serial No. 133,460.

To all whom it may concern:

Be it known that I, ELWOOD T. McGINNIS, a citizen of the United States, residing at Atlantic City, in the county of Atlantic and State of New Jersey, have invented new and useful Improvements in Coin-Holders, of which the following is a specification.

This invention relates to a coin holder which may be connected with the steering 10 posts of jitney buses or other motor vehicles of a similar nature.

The primary object of the invention is to provide a coin holder of this character having coin receiving tubes of different diameters above which is supported an inclined coin chute so constructed that when coins of different denominations are deposited therein by the operator of the vehicle or passengers, the coins will be directed into tubes 20 corresponding in diameter to the diameter of the coins.

Another object of the invention is to provide the chute with an inclined bottom having depressions therein forming shoulders 25 which insure coins of like denomination being deposited in the coin receiving tubes corresponding in diameter thereto.

A further object of the invention is to provide each tube with mechanism which 30 when operated by the operator of the vehicle will eject coins from the tubes into the hand of the operator thus allowing him to make change with rapidity and accuracy.

With these and other objects in view, the 35 invention resides in the novel combination and arrangement of parts which will be hereinafter described and particularly pointed out in the claim.

The preferred embodiment of the invention 40 has been illustrated in the accompanying drawing, although no restriction is necessarily made to the precise details of construction therein shown as changes, alterations, modifications, within the scope of the 45 claim may be resorted to when desired.

Like characters of reference denote corresponding parts throughout the several views in the drawing, in which:

Figure 1 is a face view of a coin holder 50 constructed in accordance with the invention and showing the same applied to the steering post of an automobile.

Fig. 2 is a horizontal sectional view on the line 2—2 of Fig. 1.

Fig. 3 is a vertical transverse sectional view on the line 3—3 of Fig. 1.

Fig. 4 is a bottom plan view of a portion of the coin holder showing the ejecting mechanism connected therewith.

Fig. 5 is a perspective view of one of the 60 coin ejecting slides.

Fig. 6 is a detail sectional view through a portion of the coin chute and tubes connected therewith.

Referring now to the drawing in detail, 65 the numeral 1 designates the steering post of an automobile and 2 the base of the improved coin holder, said base having an upper face 3, a bottom face 4, and sides 5 and 6.

The base 2 has formed therein elongated 70 and transversely extending slots 7 arranged in spaced relation throughout the length of the base with the slots greatly increasing in width toward one end thereof.

The upper face 3 of the base has formed 75 therein above each slot 7 a circular opening 8, the peripheral wall of which is threaded, as at 9, said opening having communication with the slots 7 and varying in size according to the width of said slots.

The bottom face 4 of the base has formed 80 therein below each slot 7 a recess 9 substantially semi-circular in shape in cross section and opening out through the side wall 6 of the base, said recesses also communicating 85 with the slots 7 and varying in diameter according to the width of the slots 7.

Depending from the bottom face 4 of the base adjacent each recess 9 is a lug 10.

A substantially square plate 11 is mounted 90 to slide in each slot 7 and corresponds in width to said slot and is provided with a centrally arranged opening 12 corresponding in diameter to the circular opening 8 in the base above the slot 7 in which the plate 95 is arranged.

The plates 11 extend at one end beyond the side wall 5 of the base and are provided on said extending end with a down-turned flange 13.

Connected with each lug 10 is one end of a coiled expansion spring 14, the other end of which is connected with the flange 13 on the plate 11 which is mounted to slide in the opening 7 above said lug, said spring normally tending to hold the flange 13 in spaced relation with the side wall 5 of the base.

One end of each plate 11 is provided in its corner with upstanding ears 15 which are normally held in contact with the side wall 6 of the base by the spring 14 and cause the 5 openings 12 in the plates to register with the circular openings in the upper face 3 of the base.

Coin tubes 16 which vary in diameter to receive coins of different denominations, 10 each has an end threadedly engaged in an opening 8 in the base corresponding to the diameter of the tube for connection therewith.

The other ends of the coin tubes 16 are 15 beveled, as at 17, and the tubes increase in height toward the end of the base in which is formed the smaller slot. Each tube 16 has extending laterally therefrom at its beveled end an attaching lug 18.

20 A coin chute 19 is supported in an inclined position by the beveled ends of the coin tubes 16, said chute being substantially triangular in shape in cross section to provide an inclined bottom wall 20 which is removably connected with the attaching lugs 18, a top wall 21, and side walls 22, said chute being provided at one end with a flared mouth 23.

The slanting bottom wall 20 of the coin 30 chute has formed therein above each coin tube an opening 24 corresponding in diameter to the inside diameter of the tube and allowing coins which pass through the chute to gain access to a tube of corresponding 35 diameter.

The coin tubes 16 which in this instance have been shown as three in number correspond in diameter to the diameter of a quarter, nickel, and dime, and are arranged 40 with relation to the flared mouth of the coin chute so that the tube which receives the dimes is nearest thereto and with the tube which receives the quarters arranged farthest therefrom.

45 The portion of the slanting bottom wall of the coin chute which extends beyond the tubes for receiving the nickels and the dimes has formed therein depressions 25 which form arcuate stop shoulders 26 and 27 50 gradually decreasing in height toward one side wall of the coin chute, the shoulder 26 being arranged adjacent the opening in the bottom of the coin chute which establishes communication between the chute and the 55 tube for receiving the dimes, while the shoulder 27 is arranged adjacent the tube for receiving the nickels.

The shoulder 26 is of less length and less 60 height than the shoulder 27, so that coins which pass through the chute having a greater diameter than the diameter of a dime will be retarded in their passage by the shoulder 26.

A clamp for the coin holder includes a 65 strip of material 28 which is offset between

its ends, as at 29, to provide the clamp with arms 30 and 31. The arm 30 is recessed, as at 32 to permit the arm to correspond to the curvature of a steering post 1 to which the clamp is connected by means of a 70 clip 33.

The arm 31 has connected therewith a strip of resilient material 34, the ends of which are curved, as at 35, to frictionally engage the end tubes of the coin holder, so 75 that the coin holder may be detachably connected with the supporting bracket as shown in Fig. 1 in the drawing.

When the coin holder has been connected with the steering post of a motor vehicle 80 as shown in Fig. 1 in the drawing and a passenger on the vehicle wishes to pay his fare and deposits in the flared mouth of the coin chute, a quarter, the same is carried down the chute by gravity and being of greater 85 diameter than a nickel or a dime passes over the stop shoulders 27 and 26 and drops through the opening in the slanting wall of the coin chute and into the largest of the coin tubes. 90

To return the passenger his change the operator of the vehicle places his hand beneath the coin holder and engages his fingers with the flanges on the plates 11 beneath the tubes holding the nickels and the dimes and by 95 moving said plates against the influence of the springs 14, the change for the quarter will be ejected by the plates from the tubes into the hand of the operator.

When a dime which is of less diameter 100 than a quarter or a nickel is dropped into the coin chute and comes in contact with the shoulder 26, the dime is deflected into the tube for holding the dimes and the correct change can be returned to the passenger by 105 the operator operating the ejecting plate beneath the tube containing the nickels.

When a nickel which of greater diameter than a dime is dropped into the coin chute, it is caused to contact with one side wall of the 110 coin chute by the inclined bottom thereof so that as the nickel moves down the chute by gravity, it passes over the shoulder 26 which is of less depth and of less length than the shoulder 27 until it contacts with 115 the shoulder 27 which serves to deflect the same into the tube for receiving the nickels.

From the foregoing description, taken in connection with the accompanying drawing, it is at once apparent, that a coin holder for 120 connection with motor vehicles has been provided in which coins of corresponding denominations dropped into a coin chute will be directed into corresponding coin receiving tubes provided with coin ejecting mechanism which enables the operator of the vehicle to make change with accuracy and rapidity. 125

Having thus described the invention, what is claimed as new, is:

A device of the class described having a base having a row of circular openings in the top thereof of different diameters and semi-circular shaped recesses in the bottom 5 of the base opening out through one side of the base and extending beneath said openings, said base having transversely extending slots therein interposed between said openings and recesses, plates in said slots 10 extending beyond the sides of said base, each of said plates having a circular opening

therein corresponding in diameter to the diameter of the opening below which the plate is mounted in the base, upstanding ears at one end of each plate, a down turned flange 15 at the opposite end of each plate, lugs on the bottom of said base contiguous to the walls of said recesses, and coil expansion springs terminally connected with said lugs and flanges.

In testimony whereof I affix my signature.

ELWOOD T. McGINNIS.
